UNITED STATES PATENT OFFICE.

DAVID N. B. COFFIN, JR., OF NEWTON, MASSACHUSETTS.

DESIGN FOR HAND-WHEEL FOR STEERING APPARATUS.

Specification forming part of Design No. 7,421, dated May 12, 1874; application filed March 11, 1874.
[Term of Patent 14 years.]

To all whom it may concern:

Be it known that I, DAVID N. B. COFFIN, Jr., of the city of Newton, in the county of Middlesex and State of Massachusetts, have invented a Design for Hand-Wheel for Steerers, &c., of which the following is a specification:

The nature of my design is fully shown in the accompanying drawings, to which reference is made.

Figure 1 shows the complete wheel. Fig. 2 shows a portion of the same enlarged. Fig. 3 shows a sectional view of a portion. Fig. 4 shows a section of the rim still further enlarged. Fig. 5 is a section of one hub, *a*, taken on line *c b*.

One feature of my design is the shape of the rim, as represented in the section shown in Fig. 4. Another feature is the shape of the hub *a*, which is, in general form, a part of a cone, having about a quarter-circle round corner at its junction, with the spoke and handle *e* joined to the rim and these parts, as shown.

Another feature is the star shown on the hubs *a*. The surfaces on the rim at *f* and *g*, forming a portion of each face of the wheel, coincide approximately with the surface of an imaginary cone or cones, whose apex would be located in the axis of the wheel near or at its center. The other surfaces of the rim, or the section which defines their form, are otherwise made up of parts of circles, as shown.

I claim—

1. The shape and configuration of the rim, hub *a*, and its star, united to form a design, substantially as described and shown.
2. The shape and configuration of the rim and taper hub *a*, united substantially as shown.
3. The shape and configuration of the taper hub *a* and the star, united substantially as described.

DAVID N. B. COFFIN, JR.
